GUIDE FOR CENTRIFUGAL SPINNING

John A. Miles, Chester, Pa., assignor to American Viscose Corporation, Wilmington, Del., a corporation of Delaware

Application September 30, 1949, Serial No. 118,957

10 Claims. (Cl. 57—76)

1
This invention relates to yarn guides adapted to control the centrifugal delivery of a strand into a rotary bucket such as is used to collect artificial filamentary material from a spinning machine therefor.

In spinning viscose rayon, for example, minute streams of viscose solutions are continuously extruded into an acid bath and coagulated into filaments which are withdrawn therefrom and passed over a series of guides and godets and through a reciprocating guide which extends centrally into a rotating bucket which collects the strand. The strand is discharged from the guide through a smooth or rounded-edged annular tip which is accurately centered within the bucket. In conventional equipment, the reciprocating guide may consist of a glass tube having a flared or funnel-shaped end portion for receiving a yarn and being interiorly constricted at several places to reduce the contact of the yarn with the inner walls of the tube and thus the friction to which the yarn passing therethrough is subjected.

The tube is usually supported within an annular sleeve or ferrule constructed of lead. The ferrule is attached to the glass tubular stem by pouring molten sulphur between the inner surface of the ferrule and outer surface of the stem. The outer surface of the ferrule is smooth and approximately cylindrical, and contiguous with a radially extending flange which enables the funnel guide to be supported within a smooth bore of a reciprocable bracket. On installations in which it is not necessary to remove the funnel during a doffing operation, the exterior surface of the ferrule may be threaded and permanently secured in threaded relationship with the bracket. The threaded surface of the ferrule is sufficiently long to permit a range of vertical adjustment of the guide with respect to the bracket.

When using apparatus such as described above, cakes of rayon are often formed in which yarn of the outer layer is curly. Generally, the wavy or curly condition of the yarn is most evident in the outermost layers, and is progressively less noticeable as the outermost windings are removed. Frequently, several hundred yards or more must be removed before straight yarn is obtained. It is also observed that winding of the yarn around the stem of the funnel guide is most likely to occur when the spinning equipment produces curly cakes. When the yarn starts winding onto the stem, the yarn already collected in the bucket rapidly backwinds onto the stem and soon sufficient yarn is collected thereon to engage

2
either the bucket cover or the bottom of the bucket. Usually, when this happens, the stem breaks and scores the inner surface of the bucket. Not only must the yarn collected and the broken funnel guide be discarded, it may be necessary to replace the damaged bucket. Extremely accurate centering of the spinning funnel, although difficult to obtain in normal production practice, may eliminate to some extent the production of curly yarns. It has been noted, however, that these objectionable winding and cake-forming conditions are more likely to occur when the size of the spinning bucket is increased; for example, it is extremely difficult to spin a cake having an outer diameter of eight inches with conventional equipment without producing curly yarn in the outer windings. Reciprocating guides having flared or bell-shaped thread-discharging portions have been heretofore used to avoid the production of curly filament or yarn, but have not been generally accepted because of the difficulty of removing yarn which inadvertently became wrapped thereabout, also because of their greater expense and bulk, susceptibility to damage from handling, and the modification required in supporting apparatus therefor.

It is an object of the present invention to prevent the formation of curly filaments or yarns while spinning or otherwise forming filamentary packages. It is another object to reduce the tendency of the yarn to wrap about the stem of a guide used to direct the strand into a rotary receiver. Still another object is to provide a guide for centrifugal spinning from which yarn occasionally wrapped thereabout may be readily removed. Another object is to provide a support for the stem portion of the funnel which supplants the conventionally applied ferrule of lead or other metal used in the construction of a funnel guide. It is also an object to provide an improved funnel guide of simple inexpensive construction which may be readily applied to existing equipment. Other objects, features and advantages will be apparent from the following description of the invention and the drawing relating thereto in which:

Fig. 1 is an elevation partly in section of a guide according to the invention, a portion of a spinning bucket, and a conventional support for the guide;

Fig. 2 is an elevation view partly in section of a modified guide; and

Fig. 3 illustrates still another modified guide.

It has been found that an annular member 55 may be incorporated into a thread guide assembly

of a bucket spinning apparatus which provides an annular thread-discharging surface of sufficient diameter to prevent the formation of curly yarn, and an outer surface from which wrapped yarn may be readily removed; moreover, the member may be used in place of the ferrule included in the construction of the conventional funnel guide to support the flared-end tubular yarn-conducting member. Accordingly, the invention concerns a strand guide comprising an inner thread conducting member supported within an outer concentric annular member which has an annular end surface spaced endwise of the thread-discharging end of the inner member. The guide is supported along an outer surface of the outer member and may be constructed to fit within a bracket such as normally provided to support a conventional funnel guide by its ferrule.

Fig. 1 illustrates a thread conducting tubular member 5 such as that to the stem of which a lead ferrule is conventionally applied adjacent the flared section 6. However, in the present invention, the need for such a ferrule is eliminated and the member 5 is supported by the upper annular edge 8 of a tube 10. The lower end portion 12 of the member 5 is centered within the tube 10 by means such as a sleeve 14 which may be constructed to fit tightly within the tube from any material resistant to the various corrosive materials which occur in the vicinity of the spinning equipment. The aperture of the sleeve or ring 14 is preferably large enough to provide a loose fit with the funnel stem and the periphery of the aperture may be rounded in an axial direction to facilitate insertion of the stem. In order that a strand passing through the member 5 may establish sufficient contact with the end-surface 15 of the tube 10, preferably the tube should extend in an axial direction beyond the member 5 sufficient distance to maintain an angle A of less than about 45 degrees between their axis and the portion of yarn path which extends between the thread-discharging ends of the members. A desirable ratio exists between the inner diameter of the member 10 and the distance between the thread-discharging ends of the members 5 and 10 when angle A is approximately 30 degrees.

The thread-engaging end of the member 5 being thus spaced inwardly of the outer member 10 in a direction lengthwise thereof from the strand-engaging surface 15, yarn bears on the surface 15 to such an extent that this surface may be considered the point of departure from the guide for thread or yarn being centrifugally deposited within a rotary bucket 17. An exteriorly threaded surface 19 permits vertical adjustment of the member 10 within the sleeve 20 to any setting needed to obtain a desired ambit of the end-surface 15 with respect to the interior of the bucket. The adjustment may be fixed by tightening a lock nut 22. Lateral adjustment of the guides is obtained by loosening a lock nut 24 in threaded relationship with the exterior threads of the flanged sleeve 20 and shifting the sleeve laterally within an aperture of the support arm 25. The annular clearance 27 is an outer portion of the aperture of the arm 25. The guide is supported by a conventional parallel bracket device of which only the support arm 25 and portions of arms 29 and 30 are shown.

Fig. 2 illustrates a guide for centrifugal pot spinning adapted to be mounted on equipment from which the guide must be removed to accomplish doffing. A glass funnel member 5

which may be identical with that shown in Fig. 1, is supported within a sleeve member 10a. The glass member rests within the sleeve 10a by contact of the outer surface of its upper flared section 6 with the inner edge of a flange 33. The sleeve 10a is supported within an exteriorly threaded sleeve 34 by engagement of the lower surface of the rim 33 with the upper surface of a sleeve 34. The rim 33 is flared to provide a peripheral surface by which the guide may be gripped by the fingers when lifting the guide from the support sleeve 34. The sleeve 34 is vertically adjustable in threaded relationship with respect to the sleeve 20a provided for lateral adjustment of the guide, such as obtained with the sleeve 20 of Fig. 1. The strand-discharging end of the funnel is centered within the sleeve 10a by a collar 14a. A ring element 36 in threaded relationship with the yarn discharging end portion of the tube 10a provides a wear-resistant surface 37 around which the strand passes. The element 36 may be fabricated from such materials as glass, porcelainized ceramic or metallic material, synthetic sapphire, or quartz.

25 An equivalent abrasive-resistant element may be attached to the tube 10a by cementing, or by clamping, such as by spring tension in the material itself, into engagement with a peripheral surface of the tube. Any thread-guiding tube member according to the invention analogous to the tube 10a may be adapted and provided with an abrasion-resistant ring element.

Fig. 3 illustrates a modified form of funnel guide having a necked tubular member 10b of which the strand-discharging rim 15b is greater in diameter than the threaded surface 19b by which the sleeve is supported. The stem of the inner member 5 is centered within the outer member by a ring member 14b secured within the member 10b. The contour of the member 10b is approximately cylindrical between the rim 15b and the threaded section 19b so that when any yarn is wound onto the guide, it winds onto this section and may be readily removed. The rim section 15b may be enlarged to any diameter which will reduce the distance which the thread has to travel after leaving the rim surface to prevent the formation of curly yarn. The practical limit to which the outer diameter of the rim section may be increased is that which does not cause interference of the member 10b with the inner surface of the package at the end of the doffing period. Preferably the rim section should be a somewhat smaller diameter than the inner diameter of the completed package so that an aperture of intermediate diameter may be maintained in the bucket cover to prevent an overflow of strand through the cover aperture. The sleeve construction of Fig. 3 is resorted to when spinning buckets of larger diameters are used so as to reduce the distance through which the yarn has to pass between the guide and the inner surface of the bucket or the cake.

Sleeves such as 10, 10a, and 10b may be formed of any material resistant to the corrosive conditions in a particular spinning operation. When spinning viscose filaments for example, such sleeves may be fabricated from materials such as hard rubber, porcelainized metal, polymers of styrene or acrylonitrile, and various laminated fabric and thermoplastic or thermosetting compositions which may or may not be coated with an inert material such as a silicone resin.

Members, typified by sleeves 10, 10a and 10b, eliminate the conventional ferrule used on funnel

guides and provide an arrangement for preventing the formation of curly yarn whereby the distance between the effective point of departure of the strand from the guide and the surface within the bucket for receiving the strand may be maintained below that which contributes to the production of curly strand. By the present invention, there is less tendency for the strand to be wrapped around the guide when the distance between the guide and the inner surface of the cake is relatively short. However, if the strand does become wrapped around the guide, the wrapped portion is not so likely to break as the stems of the conventional guides and the yarn is readily removed from the outer cylindrical surface of any one of the sleeves illustrated. The construction herein disclosed is economical and readily displaces the guides of conventional design. Substantial savings accrue from the reduction in breakage of the glass stem portions of the funnel guides as the result of the protection provided by the outer support tubes. Moreover, the inexpensive glass portion of the funnel guide may be readily replaced when it becomes broken or chipped without also discarding a ferrule such as that attached to conventional guides.

While preferred embodiments of the invention have been shown and described, it is to be understood that changes and variations may be made without departing from the spirit and scope of the invention as defined in the appended claims.

I claim:

1. A strand guide for delivering thread into a rotary bucket comprising an inner elongate member having a passageway for conducting the strand longitudinally therethrough and having an enlarged strand-receiving end portion, an outer elongate annular member having a surface at one end for engaging the exterior surface of the enlarged portion to loosely support the inner member, said outer member having an annular exterior surface adjacent the end which supports the inner member for engaging a support means and terminating at its strand-discharging end in an annular surface of greater diameter than the surface for engaging a support means, said annular surface spaced endwise of the strand-discharging end of the inner member, and means supported within the outer member for centering the strand-discharging end of the inner member therewithin.

2. A strand guide for delivering thread to a rotary bucket comprising an inner elongate member having a passageway for conducting the strand longitudinally therethrough and having an enlarged strand-receiving end portion, an outer elongate annular member having a surface at one end for engaging the exterior surface of the enlarged end portion to loosely support the inner member, said outer member having an exterior annular surface adjacent the end which supports the inner member for engaging a complementary surface of a support means, an exterior substantially cylindrical surface of the outer member which is greater in diameter than the surface which engages the support means extending axially from its strand-discharging end for a distance at least equal to the depth of the bucket, said strand-discharging end spaced beyond the strand-discharging end portion of the inner member, and means for centering the strand-discharging end portion of the inner member within the outer member.

3. A strand guide for delivering thread into a rotary bucket comprising an inner elongate mem-

ber having a passageway for conducting a strand longitudinally therethrough, said inner member having an enlarged strand-receiving end-portion and an annular strand-discharging end-surface, and an outer elongate member for supporting the inner member centrally therewithin, said outer member having an annular strand-engaging end-surface of substantially larger diameter than the strand-discharging surface of the inner member, said inner member extending substantially through the outer member with said strand-discharging surface being spaced adjacent to, and inwardly of the outer member in a direction lengthwise thereof from, said strand-engaging surface, and means for maintaining the strand-discharging surface in concentric relationship with the strand-engaging surface.

4. A strand guide for delivering thread into a rotary bucket comprising an inner tubular member having a flared end-portion for receiving a strand and an annular strand-discharging end-surface, and an outer elongate annular member for supporting the inner member concentrically therewithin, said outer member having an annular strand-engaging end-surface of substantially larger diameter than said strand-discharging surface of the inner member, said inner member extending substantially through the outer member with said strand-discharging surface being spaced adjacent to, and inwardly of the outer member in a direction lengthwise thereof from, said strand-engaging surface.

5. A strand guide for delivering thread into a rotary bucket comprising an inner tubular member having a flared end-portion for receiving a strand and an annular strand-discharging end-surface, and an outer elongate annular member for supporting the inner member concentrically therewithin, said outer member having a surface at one end for engaging an exterior surface of said flared end-portion and having an annular strand-engaging surface at the other end of substantially larger diameter than the strand-discharging surface of the inner member, said inner member extending substantially through the outer member with said strand-discharging surface being spaced adjacent to, and inwardly of the outer member in a direction lengthwise thereof from, said strand-engaging surface.

6. A strand guide for delivering thread into a rotary bucket comprising an inner tubular member having an enlarged end-portion for receiving a strand and an annular strand-discharging surface, and an outer elongate member for supporting the inner member concentrically therewithin, said outer member having a surface at one end to engage the exterior surface of said enlarged end-portion and an annular strand-engaging surface at the other end of substantially larger diameter than the strand-discharging surface of the inner member, said inner member extending substantially through the outer member with said strand-discharging surface being spaced adjacent to, and inwardly of the outer member in a direction lengthwise thereof from, said strand-engaging surface.

7. A strand guide for delivering thread into a rotary bucket comprising an inner tubular member having a flared end-portion for receiving a strand and an annular strand-discharging end-surface, and an outer tubular member having an annular surface at one end of smaller diameter than the larger diameter of said flared end-portion for engaging an exterior surface thereof to support the inner member concentrically within

the outer member, said outer tubular member having an annular strand-engaging end-surface at its other end of substantially larger diameter than said strand-discharging surface of the inner member, said inner member extending substantially through the outer member with said strand-discharging surface being spaced adjacent to, and inwardly of the outer member in a direction lengthwise thereof from, said strand-engaging surface.

8. A strand guide for delivering thread into a rotary bucket comprising an inner tubular member having a flared end-portion for receiving a strand and an annular strand-discharging end-surface, and an outer tubular member for supporting the inner member concentrically therewithin, said outer member having an end-surface for engaging the exterior surface of said flared portion and an exterior threaded peripheral surface adjacent said end-surface for engaging an interior threaded surface of a support member for the guide, said outer member having an annular strand-engaging surface at its other end of substantially larger diameter than said strand-discharging surface of the inner member, said inner member extending substantially through the outer member with said discharging surface being spaced adjacent to, and inwardly of the outer member in a direction lengthwise thereof from, said strand-engaging surface.

9. A strand guide for delivering thread into a rotary bucket comprising an inner tubular member having a flared end-portion for receiving a strand and an annular strand-discharging end-surface, and an outer elongate annular member having a surface at one end for supporting the inner member by its flared portion, a flange extending radially outwardly from the end-portion of the outer member adjacent the end-surface for supporting the inner member, said outer member having an annular strand-engaging end-surface of substantially larger diameter than the strand-discharging surface of the inner member, means for centering the inner member within the outer member, said inner member extending substantially through the outer member with said strand-discharging surface being spaced adjacent

to, and inwardly of the outer member in a direction lengthwise thereof from, said strand-engaging surface, said outer member having a smooth peripheral surface extending from the flange for engaging a complementary surface of a support for the outer member having a bore complementary to said peripheral surface.

10. A strand guide for delivering thread into a rotary bucket comprising an inner elongate member having a passageway for conducting the strand longitudinally therethrough, said inner member having an enlarged end-portion for receiving the strand and an annular strand-discharging end-surface, and an outer elongate annular member for loosely supporting the inner member in fixed longitudinal alignment therewithin, said inner member being supported by engagement of an exterior surface of its enlarged portion with an end-surface of the outer member, 15 said outer member having an annular strand-engaging surface at its other end of substantially larger diameter than the strand-discharging surface of the inner member, said outer member having a substantially cylindrical outer surface extending from its strand-engaging surface for a distance at least as long as the depth of the rotary bucket, said inner member extending substantially through the outer member with said strand-discharging surface being spaced adjacent to, and inwardly of the outer member in a direction lengthwise thereof from, said strand-engaging surface.
